CIRCULAR RELIEF GRINDER

Clyde E. Walling, Lakewood, Ohio

Application September 5, 1935, Serial No. 39,322

2 Claims. (Cl. 51—95)

This invention relates in general to metal working machines and more particularly to grinding machines for sharpening milling cutters, hobs, reamers, taps and so forth. Grinding machines of this type embody a vertically rotatable wheel adapted to be swung around a vertical axis, so as to permit of spiral tools, such as cutters, taps and reamers being sharpened between the centres of the machine. However lip or lead angles on tools can be ground with machines of this type only, by laterally offsetting the axis of the respective tool with respect to the cutting surface of the grinding wheel and then the lip or lead angle is proportionate to the offsetting of the axis of the tool and also proportionate to the diameter of the tool.

The above described method of grinding lip or lead angles on tools by offsetting its axis with respect to the grinding surface of the grinding wheel is complicated and inefficient and does not permit to properly grind tapered or taper spiral tools, such as spiral cutters, spiral taper reamers, taper spiral hobs etc., as the outside contour of such tools is distorted during grinding operations. It has been proposed to overcome the above described deficiency in grinding tapered or tapered spiral tools by swinging the wheel head on grinding machines of the type referred to around an axis inclined toward the vertical, so that the wheel, when set square with the main slide of a grinding machine is inclined to the vertical at a definite angle of clearance. However such inclined mounting of the grinding head limits the use of grinding machines thus equipped and effects a change in the size of the lip angle on straight tools proportionate to their diameter and on spiral tools proportionate to their diameter and the pitch of the spiral.

It is the general object of this invention to provide a grinding machine which permits of proper grinding of all tools, including tapered straight or spirally fluted tools etc., with any desired predetermined clearance or lip angle. This desideratum according to the invention is attained by the provision of means for tilting the grinding head of a grinding machine in a vertical plane, so as to permit of the cutting face of the grinding wheel being set to any desired inclined position with respect to the centres of the grinding machine.

With this and incidental objects in view, the invention consists in certain novel features of construction and combination of parts, the essential elements of which are set forth in the appended claims; and a preferred form of em-

bodiment of the invention is hereinafter shown with reference to the drawings accompanying and forming a part of this specification.

In the drawings:

Figure 1 is an end elevation of a grinding machine embodying the invention.

Figure 2 is a front elevation of the grinding machine shown in Figure 1.

Figure 3 is an enlarged fragmentary sectional view partly in elevation of the machine shown in Figure 1, the section being taken on line 3—3 of Figure 2, and

Figure 4 is a cross sectional view on line 4—4 of Figure 3.

In the drawings the grinding machine is mounted on a suitably constructed stand 1, which stand vertically adjustably supports a bed 2 by means of brackets 3. The bed 2, which is vertically shiftable by means of a threaded shaft 4 and gearing 5, operated by a hand wheel 6, supports a slide 7, longitudinally slidably arranged on said bed. The slide 7 is longitudinally moved upon the bed 2 by suitable means, such as a rack bar 8 and gear 9, which gear is rotated by a shaft 10 having a hand wheel 11 attached to its outer end.

A pair of lengthwise adjustable centers 12 and 14, one being fixed and the other being vertically adjustable are supported on the slide 7 and permit of axial mounting of a tool below a grinding wheel 15. This wheel is secured to a horizontally disposed spindle 16, journaled in a head 17 and will properly grind a tool supported between the centres 12 and 14, when the tool is traversed with the slide 7 on the bed 2. The spindle 16 is coupled with a motor 18 by means of a pulley drive 19 and the motor 18 is mounted on a bracket 20, which bracket laterally extends from the head 17. An adjustably mounted tool dresser 21 permits of proper shaping or dressing of the wheel 15.

The wheel head 17 consists of a wheel supporting part 22 and an inverted cup-shaped base part 23, which base part tiltably mounts the wheel supporting part 22. The base part 23 extends with its vertical flange 24 into the recessed top 25 of the stand 1 and rests thereupon by means of a circumferential shoulder portion 26. The top plate 27 of the base part 23 is radially recessed on an arc in a vertical plane, so as to provide a curved recessed seat 28 for the downwardly extended leg portion 29 of the wheel supporting part 22. This leg portion embodies two legs 30, which are integrally connected at their

lower ends by means of a curved plate 31. The plate 31 slidably rests upon the seat 28 and permits of the part 22 being tilted in a vertical plane with respect to the part 23. A slot 32 in plate 31, arranged radially with respect to the curve of said plate, and a central bore 33 in the recessed seat 28 of the base part 23 permit of the parts being tiltably clamped to each other by means of a bolt 34. This bolt engages with its head portion 35 a perforated integral cross piece 36 within the stand 1 and thus secures parts 22 and 23 to the stand, when the nut 37 resting upon a curved washer 38, fitting the curvature of the plate 31, is screwed home.

15 When it is desired to set the head 17 and therewith the grinding wheel 15 for a particular job, the nut 37 is slightly loosened so that the base part 23 can be axially rotated to the desired position by common means, such as a worm drive, as generally practiced and therefore not shown. The setting of the head can be read on a scale 38, which scale indicates the horizontal angle of head 17 with respect to the axis between the centres of the grinding machine. Then the wheel supporting part 22 is tilted to the desired angle which can be effected either manually or by any common means, all as well known in the art. The tilting of the wheel supporting part 22 with respect to the horizontal can readily be read on a scale 39. When all adjustments are made the nut 35 is again tightened and the machine is ready for operation.

20 Preferably the two scales 38 and 39 are arranged at the same side of the machine and exact 35 readings on the scales can readily be indicated

by a double finger indicator 40 secured to the stand 1 of the machine.

Having thus described my invention, what, I claim is:

1. A grinding machine embodying in combination a standard, a horizontal slide supported by said standard, work supporting means adjustably secured to said slide, a grinding wheel shaft, and a supporting head for said grinding wheel shaft, said supporting head embodying a circular base 10 horizontally rotatably secured to said standard, a bearing means for said grinding shaft and integral supporting means for said bearing means intersecting the axis of rotation of said base, said supporting means tiltably securing said 15 bearing means to said base to effect in every adjusted position of said base tilting of said bearing means and grinding shaft in a plane through the longitudinal axis of said shaft and the axis of rotation of said base. 20

2. A grinding machine as described in claim 1, wherein said horizontally rotatable base portion of said supporting head embodies an axial bore and is recessed to form a curved seat, wherein said bearing means for said grinding wheel shaft is provided with a downwardly extended, curved portion slotted substantially parallel to said shaft and slidably rested upon the curved seat of said base portion, and wherein a single clamping means secured to said standard is axially extended through the bore of said base portion and the slot in said bearing means for rigidly securing said base portion and said bearing means jointly to said standard. 30
